UNITED STATES PATENT OFFICE.

CHARLES E. GIERDING, OF NEWARK, NEW JERSEY, ASSIGNOR TO STERLING-MEAKER COMPANY, OF NEWARK, NEW JERSEY, A CORPORATION OF NEW JERSEY.

FARE-REGISTER.

No. 800,565.

Specification of Letters Patent.

Patented Sept. 26, 1905.

Application filed May 19, 1904. Renewed March 8, 1905. Serial No. 249,123.

To all whom it may concern:

Be it known that I, CHARLES E. GIERDING, a citizen of the United States of America, and a resident of Newark, in the State of New Jersey, have invented a new and useful Improvement in Fare-Registers, of which the following is a specification.

This invention relates to that subclass of duplex fare-registers in which the trip-register and permanent register are formed in common by rotary cylinders or wheels with numbered peripheries, hereinafter termed "numeral-wheels," arranged in two horizontal series, one above the other. In addition to means for simultaneously actuating the two sets of numeral-wheels for the registration of each fare the improved register is provided with actuation-indicators which conceal the new numbers on the units-wheels of the trip-register and permanent register until such wheels are moved perfectly into position, a trip-indicator showing the direction of travel and reversed in the act of resetting the trip-register, and a "not-set" signal or indicator simultaneously actuated for concealing the indications of the trip-register during the resetting operation and calling attention to any attempt to leave the same partially reset.

The present invention consists in novel combinations of parts hereinafter claimed for performing the several functions of the improved register above stated with the least possible complication and with reference to the avoidance of small and delicate parts and the reduction of springs and the like to the least possible number.

The improved register is primarily designed and adapted to be made with numeral-wheels of one and the same size, exposing to view large numerals which can be easily read at a distance and utilizing to the utmost the cubical capacity of a square or rectangular casting. Some of the features of the invention may, however, be embodied in registers of other shapes and with greater or less numerical capacity, that of the improved register hereinafter particularly described being ninety-nine thousand nine hundred and ninety-nine for the permanent register and nine hundred and ninety-nine for the trip-register.

Seven sheets of drawings accompany this specification as part thereof.

Figures 1 and 2 are respectively front and side views of the improved register. Figs. 3

and 4 are face and edge views of its hanging board or back, showing the primary actuating mechanism. Fig. 5 is a face view of the register-works with the casing and outer dial-plate removed, this and succeeding views being drawn to a larger scale as compared with Figs. 1 to 4. Figs. 6 and 7 are fragmentary face views illustrating the operation of the full-stroke device. Figs. 8 and 9 are views of the works from the lower edge, showing the edge frame of the casing in section and in elevation, respectively, and illustrating, respectively, the registering operation and the resetting operation by the positions of the movable parts. Fig. 10 is a side view of the resetting-knob detached. Fig. 11 represents a section on the line A B, Fig. 8, with the edge frame of the casing broken away to expose the actuating-slide and with the parts in position for the registering operation. Fig. 12 is a fragmentary section on the line C D, Fig. 11. Fig. 13 is a fragmentary section on the line E F, Fig. 11. Fig. 14 is a fragmentary face view illustrating the locking of the main slide during the resetting operation. Figs. 15 and 16 are edge views of the works from its right-hand side with the working parts in their position of rest in Fig. 15 and as they appear during a registering stroke in Fig. 16, with parts removed and broken away in both figures. Fig. 17 is a back view of the pawl-carrier omitted in Fig. 16. Figs. 18 and 19 are views of the respective ends of a bridge-piece omitted in Figs. 15 and 16. Figs. 20 and 21 are edge views of the works from the left-hand side of the register, showing the bell mechanism and the trip-indicator devices with the moving parts in different positions in the respective figures. Fig. 22 is a fragmentary section on the line G H, Fig. 11, showing the not-set indicator in its effective position. Fig. 23 is a back view of the bell-hammer hub in the position in which it is represented in Fig. 20. Fig. 24 is a view of the crank-wheel of the trip-indicator detached. Fig. 25 represents a section on the line I J, Fig. 11, looking inward with the parts as they appear at the end of a registering-pull. Fig. 26 represents a section on the line K L, Fig. 11, looking in the opposite direction as compared with Fig. 25 and showing the parts of the zero-stop device as they appear during the registering operation. Fig. 27 represents the same view with

the parts as they appear at the end of a re-setting operation. Fig. 28 is a side view of one of the parts shown in Figs. 25, 26, and 27; and Fig. 29 is a fragmentary section on the line M N, Fig. 27.

Like reference characters indicate corresponding parts in all the figures.

The register-casing is composed of a back plate *a*, exposed in Fig. 5, and an edge frame *b*, immediately adjoining said back plate, of cast-iron, and a front edge portion *c*, of sheet metal, and is preferably and conveniently of a substantially rectangular shape, as indicated in Figs. 1 and 2, where its exterior is shown. A metallic hanging board or back *d* is fixedly attached to the end wall within a street-car, for example, and the back plate *a* of the register-casing is attached thereto by a rigid central horn 1 at the top of the hanging-back interlocking with a staple 2 at the top of the back plate and by a central catch-lug 3 at the bottom of the hanging-back provided with a spring-projected catch-hook 4 and a lip 5 at the lower edge of the back plate of the casing interlocking with said hook. A staple *e* on the face of said lug 3 is adapted to receive the customary transverse locking-bolt (not shown) beneath said catch-hook 4. Large-sized numerals "1" to "0" on the numeral-wheels, *f*, *f*², *f*³, *f*⁴, *f*⁵ and *g*, *g*², *g*³ of a permanent register and a trip-register, respectively, appear through parallel horizontal windows *h* and *i* in the front of the casing, as in Fig. 1, as do also actuation-indicators *j* and *k*, exposed in Fig. 5, which conceal the new numbers on the units-wheels while they are being moved into position, a reversible trip-indicator 1 showing, preferably, alternate directions of travel, and a not-set indicator *m*, (exposed in Fig. 5,) which conceals the indications of the trip-register numeral-wheels during each re-setting operation. Said windows *h* and *i* are conveniently formed by one and the same sheet 6 of glass at the front of the register-casing, with a dial-plate 7 and a dial-frame 8 respectively provided with the two windows *h* and *i* in main outline and with cross-bars *n* for the same, completing a separate frame for each exposed numeral. Said dial-plate 7 is exposed to view in Fig. 1, and said dial-frame 8 is exposed in Fig. 5. Said hanging-back *d*, Figs. 3 and 4, is provided on its face with three fixed pivots 1', 2', and 3' and a pair of stop-lugs 4' and 5'. Pivoted on said pivots, respectively, are a pair of bell-crank levers *o* and *p*, the longer legs of which depend at the lower edge of the register-casing, where they are adapted to have ringing-cords attached thereto in any approved way, and a third bell-crank lever *q*, crossing those first named at their pivots and adapted to be operated by a stud 6' on the short arm of the left-hand lever *p* and by the short arm 7' of the right-hand lever *o*, which engages with a stud 8' on the back of the third lever *q*. A spiral

spring *r*, stretched from a stud 9 on the plate of the hanging-back *d* to the left-hand extremity 10 of said third lever *q*, holds the three levers *o*, *p*, and *q* normally in the positions in which they are shown in full lines in Fig. 3, 70 with the right-hand extremity 9' of said third lever *q* against the lower stop 4'. Studs 11 and 12 on the first and second levers *o* and *p*, respectively, provide for operating them alternately by the bar-shaped connections of another type of ringing device. A slot 13 in said third lever *q* receives a stud-pin 14, protruding through a slot in said back plate *a* of the register-casing, and a shutter projection 15 on said third lever *q* closes said slot when 80 the levers *o*, *p*, and *q* are at rest, so as to prevent tampering with the register therethrough. When either of said first and second levers *o* or *p* is pulled by either form of ringing device, said third lever *q* is actuated 85 with substantially uniform leverage. Its actuation by the right-hand lever *o* is represented by dotted lines in Fig. 3. The movement is limited by the second, 5', of said stop-lugs in contact with said right-hand extremity 9' 90 of said third lever *q*. Said stud-pin 14 is carried by the main slide *s* of secondary actuating mechanism, (exposed to view in Fig. 5,) &c., which slide reciprocates between stops 16 and 17 on the face of the back plate *a* and is normally held against the lower stop 17 by a retracting-spring *t*. A ratchet-rack 18 at the inner edge of said main slide *s* interlocks with a pawl 19, as in Fig. 7, as soon as the slide is moved and prevents reversing the motion of the slide until the stroke is completed, when the rack 18 passes the pawl 19, and the latter is reversed by its spring 20 and the main slide *s* is retracted by its spring *t*. 100

A pair of notched lugs 21 and 22 on the main slide *s* couple it pivotally to pawl-carriers *u* and *v*. (See Figs. 15 and 19, inclusive.) Said pawl-carriers *u* and *v* are fulcrumed, respectively, on the hubs of ratchet-wheels *w* and *x*, loose on the shafts *y* and *z* of the permanent register and trip-register, respectively, and each in mesh with a spring-pressed working pawl *a'*, pivoted to the corresponding pawl-carrier, and with a spring-pressed detent-pawl *b'*, pivoted to the adjacent right-hand side plate *c'* of the register-works. Each of said ratchet-wheels *w* and *x* is in turn coupled by dowel-pins 23 to the adjoining units numeral-wheel *f* or *g*. Said dowel-pins 23 attach the upper ratchet-wheel *w* to the units-wheel *f* of the permanent register-train direct. In the trip-register train they attach the ratchet-wheel *x* to a notched clutch-wheel *d'*, which is loose on its shaft *z* and is normally coupled to said units-wheel *g* by a tumbler *e'*, (shown detached by Fig. 28,) a stud-pin 24 on the latter being interlocked with the notched periphery of said clutch-wheel by a spring 25, stretched from said tumbler *e'* to a stud 26 within the units-wheel 120 125 130

g. The tumbler e' is attached to the units-wheel g by a pivot 27, and a spring-pressed detent-pawl f' , attached to the wheel g by a pivot 28, interlocks with the notched periphery of the clutch-wheel d' to limit the rotation of the numeral-wheel in the resetting operation. From said units-wheels f and g motion is transmitted successively to the tens-wheels f^2 and g^2 and to the hundreds-wheels f^3 and g^3 , and so on in the permanent register in a known manner, by suitable intermittent spur-gearing 29 30 31, and in the case of the trip-register wheels g^2 and g^3 like clutch-wheels d' and tumblers e' . The inner ends of the hubs of said ratchet-wheels w and x have bearings in said side plate c' and thin outer ends have like bearings in a bridge-plate g' , by which the pawl-carriers u and v are kept in place on said hubs. A notched lug 32 on one of said pawl-carriers u couples the same pivotally to a stud-pin 33 on a slide h' , which carries said actuation-indicators j and k , so as to cause the same to move simultaneously with said units-wheels and to cover the new numbers thereon until they are in their proper positions behind the windows h and i , when the indicator-slide h' is retracted simultaneously with the main slide s by the same retracting-spring t . Stop-wheels i' and j' , having teeth the reverse of those of said ratchet-wheels w and x and fast, respectively, on the outer sides of the units-wheel f of the permanent register and the units-clutch-wheel d' of the trip-register, interlock at the end of each actuating movement with the respective extremities of a stop-lever k' , so as to prevent overmovements by momentum. (Compare Figs. 11, 15, 16, and 25.) Said stop-lever k' is pivoted to the inner side of said right-hand side plate c' , and a stud-pin 34 projects therefrom through a slot in said side plate and into a cam-slot 35 in a projection on said main slide s . Normally said stop-lever k' is out of touch with both stop-wheels. When the ringing device is pulled, the main slide s cams the stop-lever k' into effective position, as in full lines in Fig. 25, and at the end of the movement a tooth on each stop-wheel i' and j' contacts with the stop-lever k' , as in Fig. 25, and both numeral-wheels are simultaneously stopped with a new number properly exposed. A shoulder 36 on said main slide s contacts with a tappet-arm 37, fast on one end of a rock-shaft l' , which extends between the two sets of numeral-wheels and through the opposite side plate m' of the works. (Compare Figs. 15, 16, 20, 21, and 23.) A torsional spring n' , surrounding said rock-shaft l' , tends to keep the extremity of said tappet-arm 37 in the path of said shoulder 36. The left-hand end of said rock-shaft l' carries an L-shaped lever 38, the lateral arm of which extends inwardly through a slot in the adjacent side plate m' and contacts with an arm of the hub 39 of the bell-hammer o' , another arm of which is normally held

against a stop-lug 40 by a striking-spring p' . After said striking-spring p' is put in tension toward the end of each registering movement said tappet-arm 37 (shown in Figs. 15 and 16) is tripped by said shoulder 38 on the main slide s and the striking-spring p' is permitted to throw the hammer o' against the bell q' , so as to attest the registration of a fare. The shaft z of the trip-register numeral-wheels $g^2 g^3$, hereinafter termed the "resetting-shaft," is movable endwise, and its right-hand end, Figs. 15 and 16, receives the screw-threaded shank of a resetting-knob r' , (shown detached by Fig. 10,) by which to pull and turn said resetting-shaft z . An intermediate frame-plate s' , in connection with the side plate c' first named, holds said trip-register numeral-wheels $g^2 g^3$ and their accessories already named against displacement by said endwise movement of said resetting-shaft z and forms, in effect, the left-hand bearing of said resetting-shaft. Said resetting-shaft z is normally held in the position in which it is shown in Figs. 1, 5, 8, and 11 by a spring t' , abutting against said intermediate frame-plate s' and reacting against a fork-lever u' , which is coupled by its fork 41 to a collar 42 at the back or right-hand side of the bell q' , the latter being carried by said resetting-shaft z and fast thereon. In such normal position of said resetting-shaft z a notched collar v' near its left-hand end is interlocked with a stud w' on the left-hand side plate m' , as in Fig. 13, and it is thus locked against rotation until the knob r' is first pulled. Next to unlocking said resetting-shaft z for rotation the effect of each pull of said knob r' is to transmit motion by means of said fork-lever u' to a slide-lock x' , which is pivotally coupled to the rear edge of said fork-lever u' , and when so actuated interlocks with a lug 43 on the main slide s , as in Fig. 14, so as to prevent ringing the bell or registering fares during the resetting operation. (Compare Figs. 9, 12, 14, and 27.) Said notched collar v' on said resetting-shaft z is provided with peripheral ratchet-teeth, which are meshed in both positions of the resetting-shaft by a detent-pawl 44, Figs. 11 and 13, pivoted to said left-hand frame-plate m' . The rotation of the resetting-shaft z is thus confined in a familiar way to one direction, which is the reverse of the registering movement. This pawl and ratchet serves, moreover, to insure a complete rotation of the resetting-shaft z when it is once pulled and turned so as to disengage the notch of said collar v' from said locking-stud w' on the left-hand frame-plate m' . When so disengaged, said locking-stud w' serves in connection with said collar v' to lock the resetting-shaft z and the parts carried thereby in its endwise movement in their new planes of rotation. (Compare Figs. 8, 9, 11, and 13.) Another effect of pulling said knob r'

- r' is to bring into working position certain attachments of said resetting-shaft z with reference to parts the positions of which are maintained by the frame-plates c' , m' , and s' for the resetting operation. Such attachments include a collar-supported stud 45 at the left-hand side of each of the trip-register numeral-wheels g g^2 g^3 , which is so moved into the plane of the notched end 46 of the tumbler e' , pivoted to the web of the numeral-wheel to the right, as in Figs. 9 and 27, and normally retracted, as aforesaid. In such resetting position of said studs 45 when the knob r' is turned, and therewith the resetting-shaft z under the control of its said pawl-and-ratchet device v' and 44, said studs 45 are turned into interlocking contact with said notched ends 46 of said tumblers e' as the latter are successively or simultaneously reached, the notched end 46 is drawn into contact with the stud-supporting collar or shaft, as in Fig. 27, the stud 24 on the tumbler being simultaneously disengaged from the notched periphery of the adjoining clutch-wheel d' , and motion is then transmitted by this means from the resetting-shaft z to each of the trip-register numeral-wheels g g^2 g^3 or such of them as may have been moved from zero during the preceding trip or half-trip, so as to turn the same backward to zero for the next trip or half-trip. Simultaneously with such adjustment of said studs 45 for the resetting operation a cam 47, carried by said resetting-shaft z , is brought in like manner into the plane of a lug 48 on a curved lever y' , pivoted to said intermediate frame-plate s' and retracted by a spring 49, stretched therefrom to a projection on said fork-lever u' as a convenient relatively fixed part. A lever-arm 50, projecting rigidly from a rock-shaft z' , parallel with said setting-shaft z , is constructed with a longitudinal slot, into which projects a stud-pin 51, carried by said curved lever y' . Said rock-shaft z' in turn carries adjacent to the left-hand side of each of the trip-register numeral-wheels g g^2 g^3 a stop-arm 52, and each of said numeral-wheels g g^2 g^3 carries a rigid stop-lug 53 to contact with the extremity of the corresponding stop-arm 52 when the numeral-wheel g , g^2 , or g^3 is reset to zero. A positive zero-stop near the periphery of each trip-register numeral-wheel is thus readily formed. The left-hand end of said resetting-shaft z forms or is provided with an elongated pinion 54, which projects through an opening in the left-hand frame-plate m' and serves to actuate the direction-indicator l . (Compare Figs. 1, 5, 8, 9, 11, 20, 21, and 24.) Said pinion 54 meshes with and rotates a spur-wheel 55, having a bearing in said left-hand frame-plate m' and provided with a crank-pin 56. The direction-indicator l is in shape, roughly speaking, a sector of one end and the periphery of a hollow cylinder. It is pivoted to said left-hand side plate

m' near the back plate a and is constructed with a central radial slot 57, into which said crank-pin 56 projects and which converts the revolutions of said crank-pin 56 into back-and-forth movements of the peripheral portion of the indicator l , which portion is preferably provided with suitable words ("In" and "Out") indicating alternate directions of travel. A large slot 58 concentric with the periphery affords a clear space through which the pinion 54 projects, and another slot 59 concentric therewith admits a screw 60, which forms a supplemental support for the indicator l and may stop the same at the respective limits of its movement. The indicator l is shown in Fig. 20 in the same position as in Figs. 1, 5, 8, and 9 and in Fig. 21 in its alternative position. It will be understood that a single movement of this indicator l is produced by each complete rotation of the resetting-shaft z , and a different trip or half-trip is thus indicated at the end of each resetting operation. At the beginning of each rotation of the resetting-knob r' and resetting-shaft z the not-set indicator m is moved into its effective position, Figs. 22 and 27, from its normal position of rest, Figs. 5, 8, 9, 12, 25, and 26. Motion for this purpose is transmitted from the knob r' and resetting-shaft z , as shown in Fig. 22, through said cam 47, curved lever y' , and slotted lever-arm 50. A stud-pin 61 projects into the slot of this arm 50 from a radial portion of the not-set indicator m , which radial portion is pivoted on said resetting-shaft z . The portion of the not-set indicator m exposable to view extends across the peripheries of the trip-register numeral-wheels g g^2 g^3 , as in Figs. 5, 8, and 9. Normally it extends across out of line with the trip-register window i , as shown in said figures and in Figs. 12, 25, and 26, being held in this position by said retracting-spring 49. (See Fig. 12.) When said cam 47 is turned in contact with said lug 48 on said curved lever y' , it moves the latter, and therewith said slotted lever-arm 50, which in turn coacting with said stud 61 on the not-set indicator m moves the latter by a quick and effective motion into the position in which it is shown in Figs. 22 and 27, where its exposable surface, preferably red, is exposed to view through the trip-register window i , and the numerals of the trip-register wheels g g^2 g^3 are concealed thereby during the resetting operation. The not-set indicator m remains in sight until the trip-indicator l is properly adjusted for the new trip or half-trip, as aforesaid, and the trip-register is reset to zero. It then drops out of sight below the trip-register window i .

It will be understood that the improved register may be made with more or less numerous numeral-wheels and with other forms of carrying mechanism in place of the spur-gearing 29 30 31, shown in the drawings, that one of the actuation-indicators j and k

may be omitted, and that features of the improved register may be used in other fare-registers without departing from the present invention, and other like modifications will 5 suggest themselves to those skilled in the art.

Having thus described said improvement, I claim as my invention and desire to patent under this specification—

1. A fare-register having, in combination with primary actuating mechanism, secondary actuating mechanism comprising a main slide reciprocated by said primary actuating mechanism, an oscillating pawl-carrier coupled to said slide, a ratchet-wheel forming by 10 its hub a bearing for said pawl-carrier and concentric therewith, spring-pressed pawls carried respectively by said pawl-carrier and by a relatively fixed support, a frame-piece and a bridge-piece attached to said frame-piece forming bearings for said hub of the ratchet-wheel, and a units numeral-wheel to which said ratchet-wheel is coupled.

2. A fare-register having, in combination with permanent register numeral-wheels and trip-register numeral-wheels in parallel horizontal series, a primary actuating mechanism and a secondary actuating mechanism common to both, the latter receiving its motion from said primary mechanism and comprising 25 a reciprocating main slide, a pair of oscillating pawl-carriers coupled to said main slide, a pair of ratchet-wheels forming by their hubs bearings for the respective pawl-carriers and concentric therewith, a pair of 30 spring-pressed pawls in mesh with each ratchet-wheel carried respectively by the corresponding pawl-carrier and by a relatively fixed support, a frame-piece and a bridge-piece attached to said frame-piece forming 35 bearings for said ratchet-wheel hubs, and coupling devices rendering the units-wheel of each of said series movable by the corresponding ratchet-wheel.

3. A fare-register having, in combination with trip-register numeral-wheels, actuating mechanism comprising a reciprocating main slide and means for transmitting registering movements from said main slide to the units numeral-wheel comprising a ratchet-wheel, a 45 clutch-wheel concentric with said ratchet-wheel and movable therewith having a notched periphery, a tumbler pivoted to said units-wheel and having a stud-pin normally interlocked with said notched periphery, and a 50 spring within said units-wheel holding said tumbler in normal position.

4. A fare-register having, in combination with an actuating-slide, registering mechanism comprising a numeral-wheel, and a casing 55 provided with a window through which the indications of said numeral-wheel are exposed to view, an actuation-indicator carried by a slide parallel with said actuating-slide, and an oscillating part transmitting motion 60 from said actuating-slide to the units numeral-

wheel and transmitting simultaneous movement to said indicator-carrying slide, whereby said indicator is made to move in unison with the periphery of said units-wheel and interposed between the same and said casing during each actuation. 70

5. A fare-register having, in combination with an actuating-slide, permanent registering mechanism, trip-registering mechanism, and a casing provided with windows through which the indications of said registering mechanisms are exposed to view, said registering mechanisms comprising numeral-wheels, and said actuating mechanism comprising a main slide common to both trains of registering mechanism, a pair of actuation-indicators carried by a slide parallel with said main slide and adapted to be interposed between the units numeral-wheels and the windows of said casing, mechanism for transmitting motion 75 from said main slide to the respective registering mechanisms, and means for simultaneously transmitting motion therefrom to said indicator-carrying slide.

6. A fare register having, in combination with permanent register numeral-wheels and trip-register numeral-wheels in parallel horizontal series, actuating mechanism common to both comprising a reciprocating main slide, a slide parallel with said main slide carrying 90 a pair of actuation-indicators movable in front of the respective units numeral-wheels, mechanism for simultaneously actuating said units-wheels and said indicators comprising a reciprocating main slide, a pair of oscillating 95 pawl-carriers coupled to said main slide and one of them coupled to said indicator-carrying slide, a pair of ratchet-wheels concentric with the respective pawl-carriers, a pair of spring-pressed pawls in mesh with each ratchet-wheel 100 carried respectively by the corresponding pawl-carrier and by a relatively fixed support, and coupling devices rendering each units-wheel movable by the corresponding ratchet-wheel. 105

7. A fare-register having, in combination with trip-register numeral-wheels and a resetting-shaft supporting said wheels and movable endwise relatively thereto, means for pulling and turning said shaft, means for transmitting rotation from said shaft to said wheels or to such of them as have been turned from zero by actuations during a given trip or half-trip, an oscillating trip-indicator, and improved means for transmitting motion from said shaft 115 to said trip-indicator, such means consisting of an elongated pinion carried by said shaft, a crank-wheel having peripheral teeth in mesh with said pinion, its wrist-pin working in a slot in said trip-indicator, and an edge plate 120 of the register-works affording a bearing for said crank-wheel and to which the indicator is pivoted, the indicator having slots concentric with its pivot to accommodate the parts extending therethrough. 130

8. A fare-register having, in combination with trip-register numeral-wheels and an end-wise-movable resetting-shaft supporting said wheels, means for pulling and turning said shaft, means for locking the same in its retracted position and for limiting its rotation to one direction, means for transmitting rotation therefrom to said numeral-wheels or such of them as have been turned by actuations during a given trip or half-trip, an oscillating not-set indicator movable in front of said numeral-wheels, and means for transmitting motion to said indicator at the beginning of each resetting operation and holding the same in its effective position until such resetting operation is completed, the same consisting of a suitable cam movable with said shaft, a lever having a relatively fixed pivot and provided with a lug engaged by the periphery of said cam, and means for transmitting motion from said lever to said indicator.

9. A fare-register having, in combination with trip-register numeral-wheels and an end-wise-movable resetting-shaft supporting said

wheels, means for pulling and turning said shaft, means for locking the same in its retracted position and for limiting its rotation to one direction, means for transmitting rotation therefrom to said numeral-wheels or such of them as have been turned from zero by actuations during a given trip or half-trip, an oscillating not-set indicator pivoted on said shaft and movable in front of said numeral-wheels, and means for transmitting motion to said indicator at the beginning of each resetting operation and holding the same in its effective position until such resetting operation is completed, the same consisting of a cam movable with said shaft, a lever having a relatively fixed pivot and provided with a lug engaged by the periphery of said cam, and a slotted lever the slot of which embraces a stud on the lever first named and a stud on said indicator in proximity to said shaft.
